UNITED STATES PATENT OFFICE.

HERBERT M. FRIENDLY, OF PORTLAND, OREGON.

TELEPHONE SYSTEM.

Application filed March 30, 1922. Serial No. 548,165.

To all whom it may concern:

Be it known that I, HERBERT M. FRIENDLY, a citizen of the United States, residing at Portland, in the county of Multnomah and State of Oregon, have invented a certain new and useful Improvement in Telephone Systems, of which the following is a full, clear, concise, and exact description, reference being had to the accompanying drawings, forming a part of this specification.

The present invention relates to telephone systems in which selector switches are employed. More specifically, the invention relates to an improved method and apparatus whereby certain mechanism of selectors is dispensed with, and apparatus units involving essentially the displaced mechanism provided. The apparatus units are arranged so that they are normally operatively related to a plurality of selectors, which it will appear, need not belong to the same numerical order. The latter is to say, that an apparatus unit may serve a plurality of selectors, which may be a mixture of first, second and third selectors, for example.

In incorporating the present invention, I provide apparatus units in smaller number, one-thirtieth as many, for example, as there are selectors. Due to the common relation of certain control elements, thus effecting the elimination of such control elements from each selector, a considerable saving in first cost and containing space is effected.

In designing and building automatic or machine switching telephonic apparatus, for example, the total first cost is often a factor which will preclude its commercial adaptability. That is to say, apparatus, which may be operatively successful, due to its cost may not be commercially admissible. The latter may refer to a comparison of costs with other methods of interconnecting, as by manual methods, for example. To this end, it is necessary to build apparatus of the general class to which the present invention relates, within a cost limit, rather than wholly to functional and service results. The latter will mean that relays, for example, must be built, which will not exceed certain costs, even though service efficiency may be sacrificed thereby, as compared to possible efficiency. It is often determined that the inefficiency which may accrue because of sacrificing efficiency and reliability to the ends of reducing costs will be off-set by the

lower first cost and the fact that a high first cost may operate to discourage the installation undertaking. Where the number of relays can be reduced, this leaves a margin which may be diverted to the ends of durability, maintenance economy and added operative functions. The latter, while possibly not imperatively necessary, may lend to the satisfaction of the service from the viewpoint of the users. Where fewer relays are necessary, those employed may be made having higher tractive torque, thus permitting stiffer and wider margins of adjustments, with attending advantages by way of more reliability. The present invention involving a common set of control relays serving a plurality of selectors, as against a specific set of control relays for each selector, entails a saving in first cost which may be applied to improve the quality and reliability of the single control relay set employed. This will insure greater reliability to the cooperative selectors and further the localization of such defectiveness as may occur from time to time.

Where a selector having a specific set of control relays becomes inoperative, the maintenance employee must assume the defectiveness of it may be caused from a defective condition in any of the component elements of the selector. Where vital elements involved in the functioning of a selector are commonly cooperative with other selectors, as in the present invention, and but a single one of the said cooperative selectors manifests inoperativeness, it may be generally assumed that the cause is resident in elements specific to the selector concerned. The arrangement as contemplated in the present invention thus circumscribes the seat of the defectiveness, and therefore, conduces to its more ready location.

The present invention also contemplates a means to prevent two cooperative antecedent switches remaining in connection with a switch both have seized. Automatic selective switches, in commercial systems are arranged with a view of forestalling a selective connection with a switch previously seized, even though the said previous seizure occurred by a very small fraction of a second before the subsequent selective test. However, the testing may manifestly occur coincidentally, making double connection possible, and moreover, this is not unusual

80

85

90

95

100

105

110

in commercial systems. Where this occurs in intermediate links, as by a selector being seized by two antecedent selectors, or by line switches, for example, there will be no listening-in on a completed connection possible, because the further progress of the call cannot take place. At least, where such an intruding condition occurs, it creates a very undesirable impression in the minds of the 10 users, and may lead to complaint which will require investigation at cost to the operating concern.

In obviating the last foregoing possibility I provide a common conductor for each selector. This conductor leads, through a marginal relay in the apparatus unit to ground. Taps are made from the common conductor to a bank contact companion to the private and line bank contacts of the 15 leading-in terminals corresponding to the selectors, the taps being made through a set of normally closed contacts on the switching relay of the respective selector. The line relay of the line switch is arranged to be connected to an auxiliary wiper, for example, when the switching relay operates, so the line relay, which has its live terminal connected to grounded battery, is then connected to the said common conductor. The marginal relay will be thus energized, but not to a degree sufficiently to operate it. However, should two line switches be in seized relation to a selector, due to the selector being seized coincidentally, the concerned apparatus unit will have two line switches related to it and consequently will have two line relays thereof in parallel energizing the 20 marginal relay in the apparatus unit. Under the latter said condition the said marginal relay will be operatively energized. The release trunk from the apparatus unit loops through a set of normally closed contacts on the said marginal relay, and this release trunk applies a ground over a common conductor, and through a second set of 25 normally closed contacts on the switching relay of each selector to the conductor leading to the corresponding bank contact engaged by the respective private wipers of accessible line switches, to maintain the line 30 switch seized in the manner well known in the art. It will be thus manifest that where two line switches seize a selector, the said marginal relay of the apparatus unit will 35 open the release trunk and cause the line switches to unseize to cause them to again hunt. The ground winding of the line relay of the apparatus unit carries a tone, audible to a calling party which has attained connection with a selector and associated apparatus unit. When the tone is perceived the calling party will know that the circuits are 40 in readiness to receive directive impulses. In the case of the line switches becoming unseized, as last referred to, wherein they will

institute a re-hunting operation, the tone will cease and be again reapplied upon a selector being again seized. The tone application being very brief will not be noticed, in view of the fact the said marginal relay disconnects the tone when it operates. In this connection, it will be noted that the line relay of the line switch will be maintained energized (though not necessarily operatively), until after the selector "cuts-in", 75 whereby the apparatus unit is operatively disconnected therefrom.

It will appear that an apparatus unit is only exclusively converted to the use of a selector upon the concerned selector becoming seized by an antecedent switch, and that it will be disconnected therefrom upon the said concerned selector "cutting-in", to be again reassociated, subject to directive control, upon the concerned selector unseizing 80 and restoring. It will thus appear that the apparatus unit is in exclusive control of a selector only for the period from the time the selector is seized, and until the selector seizes, which period will usually not be over 85 two seconds; in fact, in many instances this time will be less than a second, the time, of course, depending upon the promptness of sending the directive impulses after the selector is seized, and upon the number of impulses in the digit series sent. In view of the fact the average time of holding a connection is eighty seconds in some exchanges, it will appear that the apparatus unit may 90 in due course serve to control a large number of selectors within the average time a selector is held.

There being one apparatus unit for thirty selectors, for example, and the fact that all idle embraced selectors thereof are barred 105 when the apparatus unit is converted, it will appear that if a line becomes electrically closed, due to a trouble condition wherein the line switch will seize a selector, it will mean that all idle selectors of the group containing it will be barred against seizure, as if they were all busy. To guard against such contingency, the apparatus units are arranged with a time element relay which serves to automatically control the seized 110 selector so that it will rotate over all the bank contacts of the first level and operate an off-normal spring set by way of releasing the apparatus unit and applying a tone upon the calling line. It will also cause a 115 lamp to glow as a signal to the attendant of the condition. The selector will be restored when the condition of the line becomes normal. Only one of the apparatus units shown incorporates the last referred-to 120 scheme, but it will be understood that such function is contemplated in all, the introduction being omitted to simplify the disclosure. The same plan in disclosing has 125 been followed in other elements of the ex- 130

amplified system, it being considered evident how specifically applied devices may be generally applied.

Referring to the drawings:—

Fig. 1 is an apparatus unit A incorporating a time element device for disassociating it from a seized selector.

Fig. 2 shows a first selector FS² and related circuits. Selector FS² is cooperative with A.

Fig. 3 shows a first selector FS³ and related circuits. Selector FS³ is cooperative with A and FS².

Fig. 4 shows a second selector SS⁴ and related circuits. Selector SS⁴ is cooperative with A, FS² and FS³.

Fig. 5 is an apparatus unit A⁵.

Fig. 6 shows a second selector SS⁶ and related circuits. Selector SS⁶ is cooperative with A⁵.

Fig. 7 shows a second selector SS⁷ and related circuits. Selector SS⁷ is cooperative with FS⁹ and A⁸.

Fig. 8 is an apparatus unit A⁸.

Fig. 9 shows a first selector FS⁹ and related circuits. Selector FS⁹ is cooperative with A⁸ and SS⁷.

Fig. 10 shows two connectors C¹⁰ and C'¹⁰ having access to substations T¹⁰ and T'¹⁰. The said connectors are reached through selectors SS⁶, SS⁷ and SS⁴, and other selectors of the respective groups containing said latter selectors.

Fig. 11 shows a substation T¹¹ leading to a line switch L¹¹. The line switch L¹¹ is one of a group having access to selector FS³, and other selectors of the group containing the latter said selector.

Fig. 12 shows a substation T¹² leading to a line switch L¹². The line switch L¹² is one of a group having access to selector FS², and other selectors of the group containing the latter said selector.

Fig. 13 shows two substations T¹³ and T'¹³ leading to line switches L¹³ and L'¹³, respectively. The latter said line switches (and other line switches of the group containing them), have access to selector FS⁹, and other selectors of the group containing the latter said selector.

Fig. 14 shows connecting lines joining Figs. 9 and 15.

Fig. 15 shows connecting lines joining Figs. 7 and 10.

Fig. 16 is a diagrammatic layout of the equipment elements shown in Figs. 1 to 13, inclusive.

Fig. 17 shows the assembly of the figures to organize a system shown diagrammatically in Fig. 16, being the system chosen to elucidate the invention. Lines extending to the margins of the sheets which register with lines extending to the margins of adjacent sheets are to be understood as being the same line, respectively.

Line switches L¹¹, L¹², L¹³ and L'¹³ are of the general class, and in fact may be assumed as of the exact type as the telephone designated A in U. S. Patent No. 13,901 re-issued to Frank Newforth, April 13th, 70 1915.

Line switches L¹¹, L¹², L¹³ and L'¹³ are of the general class as shown in U. S. Patent No. 1,193,160, granted to Lamb, August 1st, 1916. The line switches L¹³ and L'¹³ are 75 modified, however, to operate in accordance with the present invention. Line switches L¹¹ and L¹² are well known in the art.

The selectors shown, when cooperated with their respectively embracing apparatus unit 80 comprise complete selectors of the general class shown in U. S. patent to Keith, Erickson and Erickson, No. 815,321, granted March 13th, 1906, of course, modified in mechanical and circuit details to operate on 85 the well known so-called two-wire principle, and in accordance with the present invention.

The connectors C¹⁰ and C'¹⁰ may be assumed as of the exact type as connector H of 90 the said cited patent to Newforth.

By referring to Fig. 16, it will be observed that there are three groups of line switches, B, C and D, each group having access to a first selector, though it will be 95 understood that a plurality of first selectors, not shown, are, in each instance, accessible. Line switches will not ordinarily have access to more than one selector embraced by an apparatus unit, though due to the fact that 100 while selectors may have corresponding bank positions in the various line switches accessible thereto, the bank contact sets accessible to the line switches will not be tested for in the same order, due to the fact that the line switches have no normal resting position. More than one selector embraced by an apparatus unit may, in fact, be accessible to a line switch or line switches. In the case 105 of selectors, it is preferred to have but one selector of a group embraced by an apparatus unit accessible to any selector, so that as a selector rotates over busy bank contacts testing for an idle selector, each set of bank contacts so tested will refer to a selector 110 embraced by a different apparatus unit than before tested. That is to say, if there are ten sets of bank contacts, referring to ten 115 selectors, there will be ten apparatus units respective to the said selectors concerned. Under the condition, if an apparatus unit embraces thirty selectors, each one of the latter said selectors will be accessible to one of thirty groups of selectors, for example. It will also appear that the selectors 120 embraced by an apparatus unit may refer to different numerical orders, so the said thirty groups of selectors may refer to a mixture of numerical orders and also of 125 groups thereof, as has been referred to in a 130

general way hereinbefore. When a selector encounters a set of bank contacts as busy, the condition may be due to the corresponding selector being operatively busy in a connection, or that the apparatus unit embracing the selector tested may be busy by one of its embraced selectors having been seized and the apparatus unit is still converted due to the said selector not having "cut-in", it 5 being remembered that when a selector is seized, all idle selectors embraced by its apparatus unit will be barred against seizure, by the apparatus unit. In view of the foregoing, should there be first, second and third 10 15 20 25 30 35 40 45 50 55 60 65

selectors an apparatus unit may embrace a selector of each of ten groups of first, second and third selectors. Where the connections to the selectors are "lapped", as is a common practice, the groupings will ordinarily, though not necessarily, contemplate that a level of a selector will not refer to more than one selector embraced by any apparatus unit. In order to make the full disclosure as brief as possible, all figures will not be described in detail specifically, where similar figures have been so described. That is, where there are line switches, selectors and apparatus units having relays and equipment elements correspondingly drawn, they are to be assumed as having the same adjustments and corresponding functions as similarly drawn and disposed ones described. To aid in identifying the various similar elements, the numerical designations thereof will have an index digit corresponding to the figure concerned where three digits comprise the designation, the last two digits corresponding to the last two figures of designations where detailed description has been made. With reference to letter designations, an exponent digit corresponding to the figure concerned serves to correlate the element with a similar element referred to in a description employing the same letter with an exponent to correspond to the concerned figure under description.

It will be assumed that a call is initiated at substation T^{12} and that the call is to be extended to substation T^{11} , the telephone number of which is "1-1-1-2." A circuit can be traced from the winding of slow-releasing line relay B^{12} , armature 51, receiver of substation T^{12} , armature 52 to grounded resting contact, the relay B^{12} actuating. Assuming that private bank contact 54 of the set 53 to 55 (inclusive) constitutes ground, a circuit can be traced from the ground on wiper 58, of the set 57 to 59, armatures 60 and 61, conductor 62 to the winding of motor magnet M^{12} , the latter said magnet attracting its armature by way of interrupting the last traced energizing path, and upon the retraction of the said armature consequent thereto the set of wipers 57 to 59 will be driven into engagement with bank contact set 63 to 65

(respectively), the described operation of the magnet M^{12} re-occurring if wiper 58 encounters ground on bank contact 64. However, it will be assumed that the bank contact 64 does not constitute ground, and therefore no ground will have been applied to conductor 62. In this connection it will be noted that the upper armature of relay B^{12} grounds the upper winding terminal of relay C^{12} , while the lower winding terminal of the said relay is attached to the conductor 62, while wiper 58 rested on bank contact 54, assumed to be grounded, so relay C^{12} is not energized under the condition. However, if no ground is applied to conductor 62, by reason of wiper 58 not receiving a short-circuit to ground through bank contact 64, the motor magnet M^{12} and the relay C^{12} will become energized in series to the upper armature of relay B^{12} , the relay C^{12} actuating, the motor magnet M^{12} not being operatively energized due to the resistance of the winding of relay C^{12} . When the armature 60 attracts, ground on the upper armature of relay B^{12} is applied through the armature 60, wiper 58 to bank contact 64 and connections. 70 75 80 85 90 95 100 105 110 115 120 125 130

Attention is particularly directed to the fact that at the time ground was assumed maintained on conductor 62, from wiper 58, battery is being derived from the motor magnet and applied through the said wiper 58 to the bank contact engaged by it, but under the assumed condition of the bank contact 54 constituting ground potential the conductor 62 will correspondingly constitute ground potential. It follows, that if there is an ohmic resistance value, such as is involved in the lower winding of slightly slow-releasing relay B^2 , for example, which is connected from ground to bank contact 64 and its multiples accessible to other line switches of the group containing L^{12} , over conductor 201, the conductor 62 will not then constitute ground, though its potential will be high enough to not operatively energize the motor magnet M^{12} . The resistance value of the lower winding of relay B^2 is high enough to not short-circuit the winding of relay C^{12} below its operative value, though high enough to restrict the current so as to not operatively energize the motor magnet M^{12} . So it will be clear that at the time relay C^{12} energizes and operates when wiper 58 engages bank contact 64, the lower winding of relay B^2 will be energized. The adjustment of relay B^2 is such that it will operate under the latter condition, though only its armature 202 need be operated at this juncture. 120 125 130

Due to the attracted condition of the upper armature of relay B^{12} and armature 60, the battery potential initially applied through the lower winding of relay B^2 will be changed to ground potential. However, since relay B^2 has attracted its armature 202 coincident with the attraction of armature 130

60, and due to the slow-releasing characteristic of relay B², the relay B² will become locked from current derived through the winding of relay C², off-normal spring 204 of first level last rotary set LR², armature 202, conductor 203, upper winding of relay B², conductor 201, bank contact 64, wiper 58, armature 60 to upper armature of relay B¹². The windings of relay B² are connected so that they energize the core with the same polarity under the described conditions, so as not to destroy the slow-releasing property thereof, in the event the armature 60 of relay C¹² should attract a brief period in advance of the closure of the armature 202 on relay B².

In this connection, attention is called to the adjustments of relay C², wherein restraining springs are shown associated with all but the lower two armatures and the upper armature thereof. These restraining springs serve to prevent the armatures operatively attracting unless the winding of relay C² is fully energized, it being understood that the upper winding of relay B² has a relatively high ohmic value. The two lower armatures of relay C² attract under the condition of relay C² energizing through the upper winding of relay B². All armatures of relay B² are now operatively attracted.

Consequent to conductor 201 becoming grounded from the upper armature of relay B¹², this ground is communicated through armature 205 to common conductor 206. From common conductor 206 the ground is applied through armatures 305 and 405 to private conductors 301 and 401, respectively, to guard the respective selectors against seizure. In this connection it will be understood that should one or both of the armatures 305 and 405 be attracted the ground on conductor 206 will not be thus communicated to the conductor corresponding. However, under the latter assumed condition, ground would be maintained on the said concerned private conductor from the succeeding switch, as will be clear presently.

At the time relay C¹² actuates the traced path including the receiver at substation T¹² is continued from armature 51, wiper 57, bank contact 63, conductor 67, armature 207, common conductor 208, upper winding of line relay G to grounded battery, and from ground, lower winding of relay G, common conductor 101, armature 209, conductor 210, bank contact 65, wiper 59 to armature 52, the relay G actuating, followed by its dependent slow-releasing relay H. Armature 102 on relay H attracting, applies ground over conductor (release trunk) 103 to common conductor 206, armature 205 to conductor 201. The latter ground is applied before the upper armature on relay B¹² retracts due to the attraction of armature 51 consequent to the line switch L¹² "cutting-in", so that no lapse of ground potential occurs to conductor 201, nor common conductor 206. That is, the relay C¹² in the line switch L¹² is maintained, and the idle selectors FS³ and SS⁴ are maintained barred against seizure by an antecedent switch. Due to armature 212 being attracted, the relays B² and C² are maintained locked, bearing in mind that relay C² is not fully energized since the upper winding of relay B² is in series with it still. It will thus appear that if armature 205 attracts, as when relay C² becomes fully energized, there will be no lapse of ground potential on conductor 201, because ground will be received back from the succeeding switch seized (as will appear presently), before relay B² becomes unlocked and its armature 212 retracts, in view of the slow-releasing characteristic of relay B².

The windings of relay G being operatively energized in series with the receiver of the substation T¹², upon the manipulation of the calling device 70 in accordance with the first digit "1", wherein relay G will de-actuate and reactuate one time responsive thereto, causing an impulse to be applied from the armature on relay G, armature 105, winding of relay J (relay H sustaining over the current lapse) common conductor 106, armature 214 to the vertical magnet VM², the latter said magnet stepping the shaft carrying wipers 215 to 218 one vertical step, incidentally operating the off-normal spring set ON². Incidental to the de-actuation of relay G, relay M will actuate and lock to grounded conductor 103. The latter function disables dash-pot relay D, the purpose of which will appear presently. Also, when relay J actuates, relay E will actuate and lock to conductor 103, and ground from conductor 103 is applied through armature 108 to the winding of shunted interrupter relay K, the latter said relay actuating and locking by way of armatures 109, 110 and 112 to conductor 103. Upon the retraction of armature 108, a circuit path is closed from grounded conductor 103, the latter said armature 108, armature 113 to the winding of relay L, and over common conductor 114, spring 220 of set LR², armature 221, to the rotary magnet RM², the latter said magnet operating by way of driving the wipers 215 to 218 into engagement with the first set of bank contacts 225 to 228, respectively. In this connection it will be noted that the lower winding terminal of relay F became grounded due to the attraction of armature 102, while the upper winding terminal of said relay F is at the time not connected to either ground or grounded battery. However, upon the actuation of relay J consequent to the sending of the first control impulse, wherein re-

76

130

lays E and K energize practically coincidentally, the upper winding terminal of relay F will have ground from conductor 103 applied to it by way of armature 112, the relay F being now inoperative by reason of being short-circuited.

It will be assumed for the present that the set of bank contacts 225 to 228, corresponding to second selector SS² is barred 10 against seizure by reason of bank contact 228 constituting ground potential, as will appear presently will so bar it. Upon the wiper 218 engaging bank contact 228, the ground received will be applied through 15 make-before-break spring 230, armature 231, common conductor 232, armatures 115 (attached to upper winding terminal of relay F), and 112 to grounded conductor 103. The latter ground is applied over common conductor 232 to the upper winding terminal 20 of relay F before armature 110 opens the locking circuit for relay K, due to the adjustment of armature 110, so the retracting of armature 112 does not remove ground 25 potential from the upper winding terminal of relay F. However, due to common conductor 232 constituting ground received from bank contact 228, upon the retraction of armature 110 a circuit will be closed from 30 ground, conductor 232, armatures 110 and 109 to the winding of relay K, the latter said relay actuating and locking through its armature 112 in the manner before described. The armature 108 being retracted 35 and constituting ground potential received from conductor 103, a circuit can be traced from said armature 108, armature 113 to the windings of relay L and the rotary magnet RM², as before set forth, the wipers being 40 advanced a further rotary step, the functioning described being continued as long as the wiper 218 receives ground from the successively engaged bank contacts.

If the bank contact 228 (or any subsequently tested bank contact engaged by wiper 218), does not constitute ground potential, the common conductor 232 will not receive ground from wiper 218, so when armature 112 retracts consequent to the relay L 45 actuating and unlocking relay K, there will not be ground potential on the upper winding terminal of relay F, though there will be battery potential thereon derived through winding of relay K, armatures 109 and 110. 50 The current ensuing through the windings of relays F and K is of such value that relay F will be operatively energized, but due to its marginal adjustment the relay K will not operate. The operation of relay F will 55 cause ground to be applied through its armature 118, common conductor 119, armature 233, conductor 203, armature 202, spring 204 to the winding of relay C², fully energizing the latter said relay and causing 60 it to operate all its armatures by way of

effecting the seizing operation of the selector FS². In this connection it will be noted that conductor 201 is now applied to ground through armature 212, conductor 206 to grounded conductor 103 and that the upper winding terminal of relay B² is now grounded through armature 233 to grounded conductor 119. In view of the armature 235 being attracted, and also, the vertical off-normal spring set ON² being operated, the lower winding of relay B² is not energized. The latter said relay will thus deactivate, consistent with its slow-releasing period. The latter period will be of such length as to permit ground to be received through 70 wiper 218 from the switch succedent, as will appear presently, whereby the ground thus received will be applied through armature 236, conductors 203, 237, spring 204 to the winding of relay C². This will maintain relay C² fully energized and it will maintain ground potential on the upper winding terminal of relay B². Ground potential derived from wiper 218 will be applied through armature 205 to conductor 80 75 85 90 95 100 105 110 115 120 125 130 135 140 145 150 155 160 165 170 175 180 185 190 195 200 205 210 215 126, ground will be applied from conductor 103, armature 127, segments 125 and 126, winding of relay J, conductor 106, armature 214 to the vertical magnet, causing the wipers 215 to 218 to be raised into alignment with the first level of bank contacts. Relay E will actuate and lock as before, because of the actuation of relay J. However, since no directive impulses have been sent, and therefore, relay G has not deactuated, relay M will not have been actuated and locked, by way of disconnecting the relay D. The armature 127 attracting consequent to the impulse being applied to the vertical magnet VM² wherein the relay J actuates, the last described energizing path is opened, followed by the closure of a path from ground, segment 128, armatures 110 and 109, to the winding of relay K, the latter said relay actuating. In view of armature 108 being retracted, a circuit can now be traced from conductor 103, armatures 108 and 113 to the windings of relay L and the rotary magnet RM², over the path before traced, the rotary magnet stepping the wipers into engagement with the first set of bank contacts. Upon the armature 110 attracting, the last traced path will become opened by reason of relay K deactuating. However, upon the armature 110 retracting the energizing path for relay K will become again closed, whereby the relay L and the rotary magnet RM² will be caused to again operate, to drive the wipers into engagement with the second set of bank contacts, the cycle of operations to drive the wipers successive steps continuing, irrespective of the condition encountered by wiper 215, until the wipers rotate-off the last set of bank contacts, and the shaft cam operates the off-normal spring set LR². The latter said set of springs operates from the first level only, though it manifestly may be permitted to operate from all levels, in case all trunks are found busy, and under the condition of the set LR² operating, the apparatus unit will be released from the operated selector FS², so it may be otherwise employed, as will appear presently.

When the set of springs LR² operate, the traced path to the rotary magnet RM² is opened at spring 220. Ground, constituting tone from source TS², will be applied to conductor 201, to maintain the line switch L¹² seized. It will also apply this ground to line conductor 210. The calling party, perceiving the tone emanating from tone source TS² will understand the condition ensuing. Conductor 67 is applied through spring 240 to the winding of relay C², disassociating spring 204, the latter said winding is thus energized in a path including the substation T¹², though it is not essential that the armatures of relay C², other than 241, 205, 209 and 207, be operated at this juncture, and the make contacts of the latter said arm-

tures need not be engaged by the said armatures. It will be clear that the operated state of the relay C² now depends upon the circuit being maintained at substation T¹². When the energizing path for relay B² becomes opened and relay C² deactuates, a circuit path is closed from ground, upper spring of set ON², armature 241 to the release magnet Re², operative to restore the shaft. The relay B² will deactuate, following the disengagement of spring 204.

The condition under which the dash-pot relay D will function as has been described will not ordinarily ensue under a condition of calling, because the time a calling party will delay after initiating a call before starting directive impulses will usually be shorter than the time required for the relay D to become effective to operating the vertical magnet VM². The prime object of the relay D is, therefore, to disassociate the apparatus unit from the last seized selector in case the line has been caused to falsely initiate a call. It will also induce calling parties to reduce delays in completing initiated calls to a minimum in order to prevent the vitiation thereof. In view of the second selector SS⁴ being embraced by apparatus unit A, it will appear that the automatic disassociation of the apparatus unit will occur under the condition of the second selector SS⁴ being seized by an antecedent switch, and a delay of the operative period of relay D thereafter occurring. The latter condition will ensue, if a false impulse is applied after falsely initiating a call, as often occurs in commercial operation. The introduction of a common or individual lamp signal in the manner as shown with relation to S³ in Fig. 3, causes the attendant to be apprised of the condition, knowing the specific condition existing.

It has been set forth how that while the common conductor 206 is grounded from the apparatus unit A, the private conductors corresponding to all selectors embraced by it are grounded; the said grounding either being set up by the apparatus unit or by the seized condition of the selector where employed in linking a connection to a succeeding switch. In view of the last foregoing, the bank contact 64' of line switch L¹² will constitute ground if the apparatus unit A is busy regardless of the busy or idle state of selector FS³ corresponding, bearing in mind that the selector FS³ belongs to a group not accessible to line switch L¹²; that is, line switches L¹² and L¹¹ belong to different groups. Of course, all bank contacts of line switches corresponding to 64 and 64' of each said group will be similarly grounded coincidentally from the conductor 206, to which they are normally attached. Elements in Fig. 11 designated by numerals, simply, are designated the same as corre-

sponding elements in Fig. 12, but with a prime added. Letter designations correspond, but have exponents indexing the specific figure concerned.

5 Going back to the conditions ensuing upon the relay C^2 fully energizing, and the relay B^2 deactuating consequent thereto, it will be clear that grounded battery applied through resistance r^2 is applied through armature 10 243, wiper 215 to bank contact 225, and attachments. The latter is for an object which will appear presently.

A circuit can now be traced from wiper 216, bank contact 226, conductor 244, armature 607, common conductor 608, upper winding of relay G^5 to grounded battery, and from grounded lower winding of relay G^5 , common conductor 501, armature 609, conductor 610, bank contact 227, wiper 20 217. The receiver of the substation T^{12} is included in the before traced path between wipers 216 and 217. The relay G^5 actuates, followed by its dependent slow-releasing relay H^5 . Armature 502 on relay H^5 25 attracting, applies ground over conductor 503, armature on relay N^5 to common conductor 606, armature 605 (also, armature 612) to conductor 601. The latter ground is applied before the armature 102 on relay 30 H retracts, due to the attraction of armatures 207 and 209 consequent to the selector FS^2 "cutting-in." Thus, no lapse of ground potential occurs to conductor 201, so the relay C^{12} in line switch L^{12} and the relay 35 C^2 in the selector FS^2 are maintained fully energized. Due to common conductor 606 being grounded, the private conductors leading to the selectors of the group embraced by apparatus unit A^5 is grounded from conductor 606 so the idle selectors embraced by A^5 will not be subject to seizure by an antecedent switch. If the idle selectors embraced by A^5 are in an operated condition, the armatures thereof corresponding to 40 605 will be attracted, and under that condition the private conductors thereof will be grounded from the succedent switch, in the manner as described with reference to armature 205 and conductor 201 in the case of selector FS^2 . Going back to the condition 45 ensuing just before the selector seized the selector SS^6 , wherein the wiper 218 did not encounter ground on bank contact 228, a circuit path can be traced from the winding 50 of relay K , armatures 109, 110 and 115, common conductor 232, armature 231, make-before-break spring 230, wiper 218, conductor 601, lower winding of relay B^6 , armature 235 to grounded off-normal spring of set 55 ON^6 , the relay B^6 actuating. In this connection it will be noted that relays B^6 and C^6 are like relays B^2 and C^2 , respectively, having in mind a difference in the wiring arrangement with reference to the top-most armatures of C^2 and C^6 and the fact the off-

normal set LR^2 normally involves the same circuit disposition with reference to relay C^2 as shown with reference to relay C^6 . Relay C^6 will actuate, following the actuation of relay B^6 , locking both latter said relays, 70 and the vertical magnet VM^6 and the rotary magnet RM^6 will be associated with conductors 506 and 514, respectively. The selector SS^6 and its converted apparatus unit A^5 are now in readiness to receive the second direct- 75 tive digit "1."

Upon the calling party at substation T^{12} manipulating the calling device thereat in accordance with the said digit "1," effectuating one open impulse, relay G^5 will de- 80 actuate and reactuate one time responsive thereto, causing ground to be applied from the armature on relay G^5 , armature 505 (relay H^5 sustaining over the current lapse) winding of relay J^5 , armature 614 to the 85 vertical magnet VM^6 , the wipers 216 to 218 being stepped into alignment with the first level of bank contacts 226 to 228, the off-normal spring set ON^6 operating. The relay J^5 will actuate coincidentally with the 90 vertical magnet, causing relay E^5 to actuate and lock through armature 527 to conductor 503. A circuit path can now be traced from the winding of relay K^5 , armature 508 to 95 grounded conductor 503, the relay K^5 actuating and locking by way of armatures 509, 510, 512 to conductor 503. When armature 508 retracts, following the impulse to the vertical magnet, a circuit path is completed from conductor 503, armatures 508, 100 513 to the winding of relay L^5 , causing armature 510 to be attracted to open the described locking path for relay K^5 . When relay L^5 is energized, ground is also applied in multiple over common conductor 514, armature 621 to the rotary magnet RM^6 , the latter said magnet operating to drive the wipers 616 to 618 into engagement with bank contacts 626 to 628. 105

Assuming for the present that bank contact 628 constitutes ground potential, due to the busy condition of the corresponding trunk, this ground will be applied over wiper 618, make-before-break spring 630, armature 631, conductor 632, armatures 515, (attached to upper winding terminal of relay F^5), 510, 509 to the winding of relay K^5 , causing it to actuate and lock through armature 512 to conductor 503 as before traced. Armature 508 being retracted, ground will be again applied from conductor 503, armatures 508 and 513 to the winding of relay L^5 and to the rotary magnet, the wipers being thus advanced a second 115 step, the cycles of operations continuing by way of stepping the wipers successive steps as long as wiper 618 receives ground to reactuate relay K^5 . The lower winding terminal of relay F^5 being grounded on conductor 503 and the upper winding terminal 120 125 130

of said relay F^5 will also be grounded from the wiper 618 by way of common conductor 632 and armature 515 as long as armature 618 receives ground from an engaged bank 5 contact, or armature 512 is attracted, so relay F^5 will be short-circuited under the conditions which ensue from the time relay K^5 first actuates until wiper 618 fails to receive ground from an engaged bank 10 contact. The operation of selector SS^6 , upon wiper 618 failing to find ground, is the same as will be described wherein bank contact 628 is assumed to not constitute ground.

Assuming that bank contact 628 does not 15 constitute ground when first engaged by wiper 618, relay K^5 will not reactuate and there will not be ground potential on the upper winding terminal of relay F^5 . On the other hand, the winding of relay F^5 becomes in a series path including the winding of relay K^5 , armatures 509, 510 to 20 grounded conductor 503, relay F^5 actuating, but due to the marginal adjustment of relay K^5 , the latter does not actuate with the 25 winding of relay K^5 in its energizing path. Armature 518 attracting applies ground over common conductor 519, armature 633, conductor 603, armature 602 to the winding of relay C^6 , fully energizing it, thus 30 causing the selector SS^6 to seize connector C^{10} . The upper winding of relay B^6 is now short-circuited, and in view of the lower winding thereof being open at armature 635, the said relay deactuates consistent with its 35 releasing period. Due to the attraction of armatures 607 and 609 relays G^5 and H^5 will deactuate, followed by relay F^5 . The relay F^5 will not deactuate, due to the intermediate relays G^5 and H^5 until the line relay 40 and release relay in the connector C^{10} have had time to actuate and apply ground back over conductor 648 to bank contact 628, in the well known manner. The actuation of the line relay in the connector C^{10} is due to its energizing in series with the receiver of the calling substation T^{12} , the armatures 607 and 609; wipers 626 and 627, and conductors 646 and 647, being included in the path. The apparatus unit A^5 is now operatively free 45 from the selector SS^6 , and subject to being converted by any idle selector embraced by it, upon any latter said selector being seized. The relays C^6 , C^2 and C^{12} are maintained 50 from the ground received over conductor 648, dependent upon the actuated condition of the line relay of the connector C^{10} , and therefore, upon the receiver being off the switch-hook at substation T^{12} .

The sending of the last two digits "1—2" 55 will cause the connector C^{10} to step its wipers vertically one level and in two rotary steps, completing the connection to the called substation T^{10} , operating the line cut-off relay LCO and signaling the latter said substation, in the well known manner. The

response at the substation T^{10} will have no operative effect, in the line switch L^{12} and selectors FS^2 and SS^6 beyond reversing the direction of current flow over the line conductors. Upon the calling party replacing 70 the receiver, thereby deenergizing the line and release relay in the connector C^{10} , the ground will be removed from conductor 648, causing relays C^{12} , C^2 , and C^6 to deactuate. The release magnets Re^2 and Re^6 will 75 restore the respective selectors.

Having in mind that there are a plurality of selectors associated in a group with FS^2 and SS^6 , respectively, and that the respective selectors of the said groups are preferably not embraced by the same apparatus unit as any other selector of the same group, it will appear that at the time selector FS^2 seized selector SS^6 it would have been possible for a selector companion to FS^2 to 80 have been coincidentally testing the selector group containing SS^6 . That is, it would be possible (though not very probable) for two selectors of the group containing FS^2 to coincidentally test and seize the selector 85 SS^6 . In such an event as last referred to there will be battery applied through resistance r^2 to common conductor 245, as well as through a similar resistance in the selector coincidentally seizing the selector 90 SS^6 , so the current applied through the winding of relay N^5 will be double that normally applied therethrough when one selector only is cooperative. The relay N^5 is 95 marginally adjusted to operate only under the condition of double current value, whereupon it will open the ground applied to common conductor 606 forthwith following the double seizure, thus removing the 100 ground for maintaining the relays C^2 and C^{12} and the corresponding relays of the coincidentally seizing selector and the relay corresponding to C^{12} of its antecedent line switch, whereupon both said selectors and 105 their respective antecedent line switches will 110 restore.

Going back to the condition ensuing forthwith upon the connector C^{10} being seized, it is manifest that the apparatus units A and A^5 are now free, so far as selectors FS^2 and SS^6 are concerned, and both said apparatus units are therefore subject to use 115 otherwise, as set forth. If a call is now initiated at substation T^{11} the line switch L^{11} will seize selector FS^3 in the manner as described where L^{12} seized FS^2 . If the call is destined to substation T^{10} the telephone 120 number of which is "1—1—1—1", the functioning will be as described with reference to the call from substation T^{12} to substation T^{10} , bearing in mind that when applying the descriptions to selectors FS^3 and SS^7 (SS^7 being embraced by apparatus unit A^8) the numerical reference numerals will have index digits corresponding to the figure num- 125 130

ber concerned, and the letter references will have exponents corresponding to the figure number concerned. The description relating to Fig. 12 may be applied to Fig. 11 by noting that the numerical designations correspond, however, having a prime added. The letter designations correspond, however, having exponents corresponding to the figure concerned. Of course, the last digit effective to setting the wipers of the connector on the wanted line bank contacts will be "1" in lieu of "2", due to the different bank position. It will also be noted that due to the connector C¹⁰ being busy in the first assumed call, the selector SS⁷ will rotate to the second set of bank contacts in lieu of seizing the first set. However, the latter functioning has been described with reference to the similar selector SS⁶.

It will be assumed that a call is initiated at substation T¹³, and then directly extended to substation T¹⁰. Upon removing the receiver from the switch-hook a circuit path will exist including the slow-releasing line relay B¹³, armature 1, receiver of substation T¹³, armature 2 to ground, relay B¹³ actuating, its upper armature applying ground to the winding of relay C¹³. The windings of relay C¹³ and the motor magnet M¹³ become in an energizing path operative to the relay C¹³ only, due to the marginal adjustment of the said motor magnet. If the private wiper 8 is assumed to receive ground from bank contact 13, this ground will be communicated to the winding of the motor magnet M¹³ by way of armatures 3 and 4 short-circuiting the winding of relay C¹³, the motor magnet operating and interrupting its described energizing circuit, and causing the wipers 7 to 10 to rotate off the set of bank contacts 12 to 15, in the manner described with reference to line switch L¹², the line switches L¹² and L¹³ being similar, with the exception that the latter said switch has an added wiper 9 and armature 16. The winding of relay B¹³ is thus applied through wiper 9 and bank contact 14 to common conductor *a* upon the actuation of relay C¹³, for an object which will appear presently.

Consequent to the wiper 8 not receiving ground from bank contact 13 at the time relay B¹³ actuates, battery potential will be applied through the lower winding of relay B⁹, armature 935 to grounded spring of set ON⁹, relays B⁹ and C⁹ functioning as referred to with relation to the similar selector FS². In view of apparatus unit A⁸ being like apparatus unit A⁵, with the exception of the introduction of the tone source T⁸, and that the designations corresponding, with due regard to the index digits of numerals, and exponents of letter designations corresponding to the figure concerned, it is not thought a detailed description will

be necessary to a comprehensive disclosure. However, it will appear that after the line switch L¹³ seizes, the winding of relay B¹³ will be in series with the winding of marginal relay N⁸, by way of armature 949 and common conductor 820, the relay N⁸ not actuating. It is not essential whether relay B¹³ remains operated, energized in series with relay N⁵. The tone source T⁸ applies tone which will be audible to the calling party upon the line switch L¹³ seizing, indicating that the equipments are in readiness to receive the first directive impulse. However, under the condition of relay N⁸ actuating, as will appear presently, the latter said tone is disconnected, so it will not be perceived by the calling party, at least perceived for a very brief period only, and will therefore not index that the conditions are such that directive impulses will be operationally effective to forwarding the call in the direction of the called line. Since the relay N⁸ is energized by way of armature 949, upon the relay C⁹ fully operating, the relays N⁸ and B¹³ will deenergize.

In view of the last foregoing paragraph, it will appear that if line switches L¹³ and L'¹³ test and seize first selector FS⁹ coincidentally the relay N⁸ will be energized by battery derived through the windings of relays B¹³ and B'¹³ in multiple, and under that condition the relay N⁸ will actuate, though marginally adjusted to not actuate when the winding of one relay, as B¹³, is connected with it, as normally occurs.

The sending of the first digit "1" will cause selector FS⁹ to operate and seize second selector SS⁴, which latter is embraced by apparatus unit A, in the manner as described with reference to selector FS². The sending of the second digit "1" will cause second selector SS⁴ (embraced by apparatus unit A) to operate in the manner as described with reference to selector SS⁶, the trunk leading to connector C¹⁰ being seized. If the latter trunk is busy, the trunk leading to connector C'¹⁰ will be selectively tested. The sending of the last two digits "1-1" will cause the connector C¹⁰ to operate and seize and signal upon the line leading to substation T¹⁰ in the manner before described when controlled from substation T¹².

The present invention thus provides a means whereby apparatus units or control mechanisms are enabled to co-operate with selector elements, not complete in themselves, whereby the said selector elements will function as complete units. Moreover, that the selectors embraced by the apparatus units, respectively, are all normally operationally related to the embracing apparatus unit, subject to normal operation forthwith upon the concerned selector element (which is not in itself a complete selector unit), be-

- ing seized. Furthermore that an apparatus unit will not be operatively associated with a selector after the selector seizes, and for the duration of the seizure, even though
- 5 the call has not been completed. It will be manifest that first and third selectors in a system employing three numerical orders of selectors may be controlled by the same apparatus unit in a call, for example, provided
- 10 the apparatus unit concerned embraces selectors in more than one numerical order (including the first and third in this instance), as is shown in the exemplified organization. The grouping arrangement of
- 15 trunks with reference to the apparatus units enables selections to be made over a bank level without testing selectors embraced by the same apparatus unit more than one time, and thus renders remote the probability of
- 20 finding a barred condition, wherein idle selector elements exist, even though apparatus units each embrace a large number of selector elements.
- The exemplified applications of the present
- 25 invention is but one of many possible applications thereof, the invention being subject to modifications without departing from its scope, defined by the claims.
- I claim:—
- 30 1. In a telephone system, a group of selective switches, a driving magnet specific to each switch, a driving control relay set for said switches common thereto and in permanent multiple relation therewith, and
- 35 means automatically self initiated forthwith following the completion of the operation of a said selective switch to disconnect the said driving control relay set from operative control thereof and to thereupon render the driving control relay set in control of any
- 40 one of the switches of the group irrespective of whether or not there is another call to the last said switches.
- 45 2. In a telephone system, a group of selective switches, a driving magnet specific to each switch, a driving control relay set for said switches common thereto and in permanent multiple relation therewith, means automatically self initiated forthwith
- 50 following the completion of the operation of a said selective switch to disconnect the said driving control relay set from operative control thereof while leaving the latter said switch busy and to thereupon render the driving control relay set in control of any
- 55 one of the idle switches of the group irrespective of whether or not there is another call to the last said switches, and means responsive to the seizure of an idle one of the
- 60 selective switches of the group while the first one is still busy to bar any idle selective switches of the group against seizure.
3. In a telephone system, a group of selective switches, a driving magnet specific
- to each switch, a driving control relay set 65 for said switches common thereto and in permanent multiple relation therewith, means automatically self initiated forthwith following the completion of the operation of a said selective switch to disconnect the 70 said driving control relay set from operative control thereof while leaving the latter said switch busy and to thereupon render the driving control relay set in control of any one of the idle switches of the group irrespective of whether or not there is an idle call to the last said switches, and means responsive to the seizure of another one of the selective switches of the group while the first one is still busy to bar any idle selective 75 switches of the group against seizure, until the last seized selective switch has been fully operated.
4. In a telephone system, telephone lines, a group of selective switches, a driving 80 magnet specific to each switch, means for seizing said switches by said lines for extending calls from said lines, a common driving control relay set for said switches and in permanent multiple relation therewith, and means whereby the driving control relay set will be thereupon temporarily converted to the exclusive operative relation with any selective switch seized for the duration of its driving period and disconnected automatically immediately upon the cessation of the driving period.
- 85 5. In a telephone system, telephone lines, a group of selective switches, a driving magnet specific to each switch, a common driving control relay set for said switches, means for seizing said switches by said lines for extending calls from said lines, means whereby the driving control relay set will be temporarily converted to the exclusive operative relation with any selective switch 90 incidental to the seizure of the switch for the duration of the driving period only, and means the operation of which is automatically self initiated for forthwith thereafter connecting the control relay set in multiple driving relation with all idle selective switches of the group.
- 100 6. In a telephone system, telephone lines, a group of selective switches, a driving magnet specific to each switch, a common driving control relay set for said switches, means for seizing said switches by said lines for extending calls from said lines, means whereby the driving control relay set will 105 be temporarily converted to the exclusive operative relation with any selective switch incidental to the seizure of the switch for the duration of the driving period only, and means the operation of which is automatically self initiated for forthwith thereafter connecting the control relay set in multiple driving relation with all idle selective switches of the group.
- 110 7. In a telephone system, telephone lines, a group of selective switches, a driving magnet specific to each switch, a common driving control relay set for said switches, means for seizing said switches by said lines for extending calls from said lines, means whereby the driving control relay set will 115 be temporarily converted to the exclusive operative relation with any selective switch incidental to the seizure of the switch for the duration of the driving period only, and means the operation of which is automatically self initiated for forthwith thereafter connecting the control relay set in multiple driving relation with all idle selective switches of the group.
- 120 8. In a telephone system, telephone lines, a group of selective switches, a driving magnet specific to each switch, a common driving control relay set for said switches, means for seizing said switches by said lines for extending calls from said lines, means whereby the driving control relay set will 125 be temporarily converted to the exclusive operative relation with any selective switch incidental to the seizure of the switch for the duration of the driving period only, and means the operation of which is automatically self initiated for forthwith thereafter connecting the control relay set in multiple driving relation with all idle selective switches of the group.

switches of the group, whereby it will become in exclusive driving control of the next selective switch of the group seized.

7. In a telephone system, a group of selective switches, a driving control relay set for said switches common thereto and in permanent multiple relation therewith, a calling line, means for initiating the call from the calling line and for seizing an idle selective switch of the group together with the associated relay set, and means operative automatically self initiated at the termination of a predetermined period after seizing the selective switch for disconnecting the control relay set without restoring the selective switch.

8. In a telephone system, a group of selective switches, a driving control relay set for said switches common thereto, a calling line, means for initiating the call from the calling line and for seizing an idle selective switch of the group together with the associated relay set, and means operative automatically self initiated at the termination of a predetermined period after seizing the selective switch for disconnecting the control relay set without restoring the selective switch.

9. In a telephone system, a group of directional selective switches, a calling line, means for initiating a call from the calling line and for seizing an idle directional selective switch of the group, and means the operation of which is automatically self initiated from the switch seized at the termination of a predetermined period after seizing the selective switch for initiating the operation of the said seized selective switch from normal position.

10. In a telephone system, a group of directional selective switches, a calling line, means for initiating a call from the calling line and for seizing an idle directional selective switch of the group, and means the operation of which is automatically self initiated from the switch seized at the termination of a predetermined period after seizing the selective switch for initiating a predetermined directive operation of the said seized selective switch from normal position.

11. In a telephone system, a group of directional selective switches, a driving control relay set for said switches common thereto, a calling line, means for initiating a call from the calling line and for seizing an idle selective switch of the group together with the associated relay set, and means the operation of which is automatically self initiated from the switch seized at the termination of a predetermined period for initiating directive operation of the seized selective switch from normal position and for operatively disconnecting the

control relay set from the seized selective switch while leaving the switch operated.

12. In a telephone system, a group of directional selective switches, a driving control relay set for said switches common thereto, a calling line, means for initiating a call from the calling line and for seizing an idle selective switch of the group together with the associated relay set, means the operation of which is automatically self initiated from the switch seized at the termination of a predetermined period for initiating directive operation of the seized selective switch from normal position and for operatively disconnecting the control relay set from the seized selective switch, and a signal means to indicate that the predetermined period has elapsed.

13. In a telephone system, a group of selective switches, a driving control relay set for said switches common thereto, a calling line, means for initiating a call from the calling line and for seizing an idle selective switch of the group together with the associated relay set, and means automatically self initiated from the switch seized operative at the termination of a predetermined period for disassociating the control relay set from the seized selective switch and rendering it available for use with the other switches common thereto.

14. In a telephone system, calling lines terminating in selective switches, other selective switches accessible from the first said selective switches, means for barring a said other selective switch against subsequent seizure when seized, means for any of the first said selective switches to seize any of the second said selective switches, and means operative in the event more than one of the first said selective switches coincidentally seize an accessible said switch to destroy the seizure by the switches.

15. In a telephone system, calling lines terminating in selective switches, other selective switches accessible from the first said selective switches, and means operative in the event more than one of the first said selective switches coincidentally seize an accessible said switch to destroy the seizure by the switches.

16. In a telephone system, a plurality of groups of trunking switches, a plurality of groups of trunk lines each line leading to one of said trunking switches, a common control relay for each group of trunking switches normally operatively related thereto and in permanent multiple relation therewith, and groups of calling lines leading to groups of corresponding selective switches respectively, each of the latter said switches having access to a said group of trunking switches, the groups of trunking switches and the groups of selective switches not

corresponding, each of the said selective switches having access to only one trunking switch related to a common relay.

17. In a telephone system, a plurality of groups of trunking switches, a plurality of groups of trunk lines each line leading to one of said trunking switches, a common control relay for each group of trunking switches normally operatively related thereto and in permanent multiple relation therewith, and calling lines leading to selective switches respectively, each of the latter said switches having access to a said group of trunking switches, each of the said selective switches having access to only one trunking switch related to a common relay.

18. In a telephone system, a plurality of groups of trunking switches, a plurality of groups of trunk lines each line leading to one of said trunking switches, a common control relay for each group of trunking switches normally operatively related thereto and in permanent multiple relation therewith, groups of calling lines leading to groups of corresponding selective switches respectively, each of the latter said switches having access to a said group of trunking switches, the groups of trunking switches and the groups of selective switches not corresponding, each of the said selective switches having access to only one trunking switch related to a common relay, and automatic means operative upon a trunking switch becoming seized to convert the said relay to the exclusive use of the trunking switch seized.

19. In a telephone system, a plurality of groups of trunking switches, a plurality of groups of trunk lines each line leading to one of said trunking switches, a common control relay for each group of trunking switches normally operatively related thereto and in permanent multiple relation therewith, calling lines leading to selective switches respectively, each of the latter said switches having access to a said group of trunking switches, each of the said selective switches having access to only one trunking switch related to a common relay, and automatic means operative upon a trunking switch becoming seized to convert the said relay to the exclusive use of the trunking switch seized.

20. In a telephone system, a plurality of groups of trunking switches, a plurality of groups of trunk lines each line leading to one of said trunking switches, a common control relay for each group of trunking switches normally operatively related thereto and in permanent multiple relation therewith, groups of calling lines leading to groups of corresponding selective switches, each of the latter said switches having access to a said group of trunking switches, the groups of trunking switches

and the groups of selective switches not corresponding, each of the said selective switches having access to only one trunking switch related to a common relay, and automatic means operative upon a trunking switch becoming seized to convert the said relay to the exclusive use of the trunking switch seized, and means operative incidental to the seizure by a said trunking switch to disconnect its said relay from operative relation with it.

21. In a telephone system, groups of first selective switches, groups of second selective switches, each latter said switch belonging to a different numerical order, trunk lines leading from the first selective switches terminating in the second selective switches respectively, and common second switch operating relay sets, there being a second selective switch of each group associated with a common relay set and in permanent multiple relationship therewith.

22. In a telephone system, a calling station, a selective switch, means for connecting the station to the switch, a timing mechanism, and means including the timing mechanism for audibly signaling the station after the station has been connected to the switch for a predetermined period of time dependent upon the switch not being selectively operated after said connection.

23. In a telephone system, a calling station, a selective switch, connecting terminals, means for connecting the calling station to the switch, means for selectively operating the switch controlled from the station to select said terminals, a timing mechanism, and means including the timing mechanism for audibly signaling the station after the station has been connected to the switch for a predetermined period of time if the switch has not been selectively operated to select said terminals during the time the station has been connected to the switch.

24. In a telephone system, a calling station, a selective switch, means for connecting the calling station to the switch, means for directly operating the switch controlled from the station, a timing mechanism, means including the timing mechanism for audibly signaling the station after the station has been connected to the switch for a predetermined period of time and means controlled from the station to disable last said means from being applied.

25. In a telephone system, a calling station, a calling line, a selective switch, means for connecting the station over the calling line to the switch, a timing mechanism, means for selectively operating the switch controlled over the line, and means including the timing mechanism for audibly signaling the station over the line after the sta-

125

tion has been connected to the switch for a predetermined period of time if the switch has not been selectively operated during the time the station has been connected to the switch.

26. In a telephone system, a calling station, a calling line, a called line, a selective switch, a signal device, a timing mechanism, means for connecting the said station over the calling line to the switch, means for directly step operating the switch over the line from the station to extend the calling line towards the called line, means whereby if the switch is not directly step operated within a predetermined time after the said connection is made the timing mechanism will operate the signal device to indicate the condition, and means whereby the switch will be disabled from being directly step operated to extend the calling line towards the called line consequent upon the operation of the timing mechanism.

27. In a telephone system, a calling station, a calling line, a called line, a selective switch, means for connecting the station over the calling line to the switch, a timing mechanism, a tone source, means for directly step operating the switch controlled over the line to extend the calling line towards the called line, and means including the timing mechanism for applying the tone source over the calling line audible to the calling station after the station has been connected to the said switch for a predetermined period of time if the switch has not been directly step operated during the time the station is connected to the switch.

28. In a telephone system, a calling station, a calling line, a called line, a selective switch, means for connecting the station over the calling line to the switch, a timing device, a tone source, means for directly step operating the switch controlled over the line to extend the calling line towards the called line, means including the timing device for applying the tone source over the calling line audible to the calling station after the station has been connected to the said switch for a predetermined period of time if the switch has not been directly step operated during the time the station is connected to the switch, and means whereby the application of the tone source will be disabled from being initially applied if the switch is step operated within the said predetermined period.

29. In a telephone system, a calling station, a calling line, a selective switch, a set of movable terminals on the switch, sets of fixed terminals cooperative with the movable terminals, means for connecting the calling station over the calling line to the switch, means directly controlled over the calling line for selectively testing the fixed terminals by the movable terminals whereby the first idle fixed terminal set tested will be seized by the switch, and automatically applied means whereby if a predetermined period of time elapses after the said connecting of the calling station the switch will be caused to move its movable terminals from normal position over the sets of fixed terminals.

30. In a telephone system, a calling station, a calling line, a selective switch, a set of movable terminals on the switch, sets of fixed terminals cooperative with the movable terminals, means for connecting the calling station over the calling line to the switch, means directly controlled over the calling line for selectively testing the fixed terminals by the movable terminals whereby the first idle fixed terminal set tested will be seized by the switch, and automatic means whereby if a predetermined period of time elapses after the said connecting of the calling station the switch will be caused to move its movable terminals from normal position over the sets of fixed terminals.

31. In a telephone system, a calling station, a selective switch, a set of movable terminals on the switch, sets of fixed terminals cooperative with the movable terminals, means for connecting the calling station to the switch, directive means for selectively testing the fixed terminals by the movable terminals whereby the first idle fixed terminal set tested will be seized by the switch, and automatic means for causing the movable terminals to pass over the fixed terminals whether idle or busy depending upon when the switch is operated with respect to the time the calling station is connected to the switch.

32. In a telephone system, a calling station, an automatic selective switch mechanism, a set of movable terminals of the switch mechanism, sets of fixed terminals cooperative with the movable terminals, means for connecting the calling station to the switch, manually operated control means for directly setting the movable terminals of the switch with connective relation to the fixed terminals, and automatically applied means for setting the movable terminals with relation to the fixed terminals.

33. In a telephone system, a calling station, a selective switch mechanism, a set of movable terminals of the switch mechanism, sets of fixed terminals cooperative with the movable terminals, means for connecting the calling station to the switch, a timing device, means for directly setting the movable terminals of the switch with relation to the fixed terminals, and automatic means including the timing device the effective operation of which is self controlled for setting

the movable terminals with relation to the fixed terminals.

34. In a telephone system, a calling station, a selective switch mechanism, a set of movable terminals of the switch mechanism, sets of fixed terminals cooperative with the movable terminals, means for connecting the calling station to the switch mechanism, a timing device, means for directly setting said movable terminals of the switch mechanism with relation to the fixed terminals automatically applied means including the timing device for alternatively setting said movable terminals with relation to the fixed terminals, and automatically applied means for then rendering the timing device subject to use with other said switch mechanism not used in the initial operation.

35. In a telephone system, a calling station, an automatic selective switch mechanism, a set of movable terminals, sets of fixed terminals cooperative with the movable terminals, means for connecting the calling station to the switch mechanism, manually operated control means for directly operating the movable terminals in coordinate directions to set the movable terminals with relation to the fixed terminals, and means independent of last said means the operation of which is self initiated for alternatively operating the movable terminals in coordinate directions for setting the movable terminals with relation to the fixed terminals.

36. In a telephone system, a calling station, a selective switch mechanism, a set of movable terminals, sets of fixed terminals cooperative with the movable terminals, means for connecting the calling station to the switch mechanism, means for directly operating the moving terminals in coordinate directions to sweep the fixed terminals, and automatically applied means for alternatively operating the movable terminals in coordinate directions to sweep the fixed terminals.

37. In a telephone system, a calling station, a selective switch mechanism, a set of movable terminals, sets of fixed terminals cooperative with the movable terminals, means for connecting the calling station to the switch mechanism, a timing device, means for directly operating the moving terminals in coordinate directions to sweep the fixed terminals, and means including the timing device the operation of which is self initiated at a predetermined time after the calling station is connected to the switch for alternatively operating the movable terminals in coordinate directions to sweep the fixed terminals.

38. In a telephone system, a calling station, a switch mechanism, movable terminals, and fixed terminal sets cooperative with certain of the movable terminals,

means for directly controlling the operation of the switch mechanism to cause certain of the fixed terminals to be swept by certain of the movable terminals, and alternative means the operation of which is automatically applied for causing certain of the movable terminals to sweep certain of the fixed terminals.

39. In a telephone system, a plurality of selective switches, a trunk line having common terminal sets accessible from the switches respectively, and automatic means for disconnecting the switches from connection with the trunk if more than one said switches are coincidentally in connection with the terminals of the trunk line.

40. In a telephone system, a plurality of selective switches, a trunk line having common terminal sets accessible from the switches respectively, a relay energized from all switches connected with the trunk lines, the said relay being operatively energized only when energized from a plurality of said switches coincidentally, and restoring mechanism in the respective switches subject to control of the said relay when its switch is connected to the trunk whereby when a plurality of switches have become coincidentally connected to the trunk they will be caused to restore from the trunk.

41. In a telephone system, a calling station, a timing device, a wiper selective switch having a vertical wiper movement to move the wipers into alignment with a desired level and a rotary movement to then move the wipers over fixed bank contacts, means for directly operating the switch from the calling station to move its wipers over the fixed bank contacts, and automatic means the operation of which is initiated by the timing device for alternatively operating the wipers of the switch vertically into alignment with the said desired level and then rotarily over the fixed bank contacts.

42. In a telephone system, a calling station, a timing device, a wiper selective switch having a vertical wiper movement to move the wipers into alignment with a desired level and a rotary movement to then move the wipers over fixed bank contacts, means for directly operating the switch to move its wipers over the fixed bank contacts, and automatic means the operation of which is initiated by the timing device for alternatively operating the wipers of the switch vertically into alignment with the said desired level and then rotarily over the fixed bank contacts.

43. In a telephone system, a calling station, a calling line, a selective switch, a set of movable terminals of the switch, sets of fixed terminals cooperative with the movable terminals, means for connecting the calling station over the calling line to the switch,

means directively controlled over the calling line for selectively testing the fixed terminals by the movable terminals whereby the first idle fixed terminal set tested will

- 5 be seized by the switch, and automatically applied means whereby if a predetermined period of time elapses after the said connecting of the calling station to the switch and the first said means has not been operated the switch will be caused to move its movable terminals from normal position to an off-normal position.

44. In a telephone system, a calling station, a plurality of selective switches, a common control mechanism for said switches, a set of movable connective terminals for each said switches, sets of fixed terminals cooperative with the respective said movable terminals, a timing device, means including said 15 common control mechanism for directly setting the movable terminals of only a single said switch with connective relation to the corresponding fixed terminals thereof, and automatically applied means including the 20 timing device for alternatively setting last said movable terminals with relation to the corresponding fixed terminals and for thereupon rendering the control mechanism subject to use in controlling another of said 25 switches.

45. In a telephone system, a calling station, a plurality of selective switches, a common control mechanism for said switches, a set of movable connective terminals for 30 each said switches, sets of fixed terminals cooperative with the respective said movable terminals, a timing device, means including said common control mechanism for directly setting the movable terminals of only 35 a single said switch with connective relation to the corresponding fixed terminals thereof, automatically applied means including the timing device for alternatively setting last said movable terminals with relation 40 to the corresponding fixed terminals, means for thereupon destroying the control of the operated switch by the common control mechanism and for rendering the control mechanism subject to use in controlling another of said 45 switches.

46. In a telephone system, calling lines terminating in selective switches, other selective switches accessible from the first said selective switches, and a marginally adjusted 50 relay operative only in the event more than one of the first said selective switches coincidentally seize an accessible said switch to destroy the seizure by the switches.

47. In a line connecting system, calling lines terminating in selective switches, other switches accessible from the first said switches, and a marginally adjusted relay common to the first said switches energized responsive to a first said switch seizing a

second said switch and operative only in 65 the event two first said switches have seized coincidentally for destroying the seizure of the switches.

48. In a line connecting system, calling lines terminating in connective switches respectively, other switches accessible from first said switches, a marginally adjusted relay common to second said switches, means for energizing said relay responsive to a first said switch seizing a second said switch, means for operatively energizing said relay responsive to only a plurality of first said switches becoming in seizure with a single second said switch, and means responsive to the operation of the relay for 70 75 destroying the seizure of the said seized switches.

49. In a line connecting system, calling lines terminating in connective switches respectively, other switches accessible from first said switches, a marginally adjusted relay common to second said switches, means for energizing said relay responsive to a first said switch seizing a second said switch, means for operatively energizing said relay responsive to only a plurality of first said switches becoming in seizure with one or more of second said switches which are not in a fully operated state, and means responsive to the operation of the relay for 80 85 destroying the seizure of the said seized switches.

50. In a line connecting system, calling lines terminating in connective switches respectively, other switches accessible from first said switches, a marginally adjusted relay common to second said switches, means for energizing said relay responsive to a first said switch seizing a second said switch, means for operatively energizing said relay responsive to only a plurality of first said switches becoming in seizure with a corresponding plurality of second said switches which are not in a fully operated state, and means responsive to the operation of the 90 95 relay for destroying the seizure of the said seized switches.

51. In a telephone system, calling lines terminating in selective switches, other selective switches accessible from the first said selective switches, and a marginally adjusted relay common to the first said switches operative only in the event more than one of the first said selective switches coincidentally seize an accessible said switch to destroy the seizure of one of the switches.

52. In a telephone system, calling lines terminating in connective switches, other connective switches accessible from the first said connective switches, and a marginally adjusted relay common to the first said switches operative only in the event more than one of the first said connective switches

coincidentally seize an accessible said switch to destroy the seizure of one of the switches.

53. In a telephone system, calling lines terminating in connective switches, other connective switches accessible from the first said connective switches, and a marginally adjusted relay operative only in the event

more than one of the first said connective switches coincidentally seize an accessible said switch to destroy the seizure by the switches. 10
In witness whereof, I hereunto subscribe my name this 24th day of March A. D., 1922.

HERBERT M. FRIENDLY.
